UNITED STATES PATENT OFFICE.

JOHN F. O'CONNOR, OF CHICAGO, ILLINOIS.

JOURNAL-BOX LID.

1,120,230.

Specification of Letters Patent.

Patented Dec. 8, 1914.

Application filed January 13, 1909. Serial No. 472,004.

To all whom it may concern:

Be it known that I, JOHN F. O'CONNOR, a citizen of the United States, residing in Chicago, in the county of Cook and State of Illinois, have invented a new and useful Improvement in Journal-Box Lids, of which the following is a specification.

My invention relates to improvements in journal boxes and lids therefor; and more particularly to journal boxes for use upon passenger or other cars, which are frequently stopped at a station where the passenger platforms interfere with or cramp the room of the car inspector or oiler, with ordinary journal boxes having the lids thereon hinged at their upper ends.

The object of my invention is to provide a journal box and lid suitable for use upon passenger cars, which will be of a simple, efficient and durable construction, in which the lid may be hinged at its lower end so that the passenger platforms will not interfere with the convenient inspection and packing and oiling of the journal and in which the lid, although hinged at its lower end so that its own gravity will not tend to swing it shut in the event of accidental opening, will nevertheless have means for keeping it certainly and reliably and tightly and securely closed, and in which the closure means of the lid will also effectually prevent rattling and jarring movements of the lid in respect to the journal box and consequent wear and speedy destruction.

To practically accomplish this result, and herein my invention consists, I provide the journal box at the lower edge of its opening with an integral trunnion or hinge member and with a curved spring seat socket adjacent thereto and provide the lid with a segmental hinge member at its lower end, and with a spring seat socket adjacent thereto, and combine with these parts a strong, stiff, C shaped spring formed of flat spring steel, and provided with pivot coils at its ends adapted to fit and turn in the spring seat sockets of the journal box and lid, so that the lid may swing open approximately in line with the inclined or curved outer bottom end wall of the journal box without greatly increasing the distance between the spring seat sockets on the journal box and lid and consequent strain and tension upon the spring; thus enabling an exceedingly strong spring to be employed, and one which will act to certainly and reliably hold a lid,

hinged at its lower end, securely and firmly closed, while at the same time firmly and tightly clamping both the lower or hinge end of the lid and the upper or free end of the lid snugly against the journal box, and thus effectually preventing access of cinders or dirt thereto.

My invention further consists in the novel construction of parts and devices and in the novel combinations of parts and devices herein shown and described, and more particularly specified in the claims.

In the accompanying drawing forming a part of this specification, Figure 1 is a central, vertical, longitudinal section of a journal box and lid embodying my invention. Fig. 2 is an enlarged detail vertical section showing the hinge members and spring seat sockets of the journal box and lid. Fig. 3 is a detail inside plan view of the lid. Fig. 4 is a detail front view showing the hinge member or trunnion on the journal box. Fig. 5 is a detail section on line 5—5 of Fig. 1 and Fig. 6 is a detail section on line 6—6 of Fig. 1.

In the drawing, A represents the journal of a passenger car axle, B the journal bearing, C the wedge, D the journal box, E the dust guard fitting in a slot in the journal box, F the lid and G the C-shaped spring.

The journal box is provided at the upper edge of its outer inclined bottom wall D¹ with an integral hinge member or trunnion d and with a semi-circular spring seat socket d¹ adjacent thereto.

The hinge lid F is provided at its lower end with a hinge member f, preferably of a segmental socket form adapted to fit and partially embrace the trunnion d at the lower end of the opening D² in the journal box and also with a semi-circular spring seat socket f¹ adjacent to said hinge member.

The spring G is formed of flat plate steel curved into a C-shape and provided at its ends with circular pivot coils g g adapted to fit and turn in the spring seat sockets d¹ f¹ on the journal box and lid. As the lid F is hinged at its lower end to the upper edge of the inclined outer bottom end wall D¹ of the journal box, the gravity of the lid will not tend to close it or to hold it closed under the jarring action of the journal when the train is in motion, and I therefore combine with the journal box and lid, an exceedingly strong spring G, the same extending preferably in width substantially

the full width of the lid, and being formed of sheet steel so that this spring will by its own tension serve to certainly and reliably hold the lid closed and also enable the lid to be at the same time practically and conveniently opened. The coöperating spring seat sockets on the journal box and lid are relatively arranged in respect to the axis or center about which the lid turns in opening 10 so that the distance between these spring seats will not be materially increased when the lid is open from what it is when the lid is closed. When the lid is open, as indicated in Fig. 1 so that it projects substantially in line with the outer bottom end wall D^1 of the journal box, the line joining the spring seat sockets $d^1 f^1$ of the journal box and lid will approach near but not quite to the center of the trunnion d , so that the friction 15 between the hinge member of the lid and the hinge member of the journal box under the clamping action of the strong spring G will serve to retain the lid in its open position while the car is stationary, and at the 20 same time enable the spring G to overcome the gravity of the lid and automatically turn the lid upward and inward on its lower end hinge and thus close it, when the equilibrium between the tension of the spring and the 25 friction of the hinge members is overcome by the jarring action of the journal on the journal box and lid when the train is under motion.

The strong spring G firmly clamps the lid 30 against the journal box both at its lower or hinged end and at its upper or free end, and thus tightly closes the journal box to exclude 35 dust and cinders and also prevents any jarring or rattling movement of the lid in respect to the journal box and the wear and cutting of parts incident thereto.

The lid F has a stop shoulder f^2 , which by engagement with the corresponding stop shoulder d^2 on the journal box limits the 40 opening movement of the lid. The journal box is also preferably provided with a guard wing d^3 having a curved face d^4 , and the lid with a guard wing f^3 having a curved outer face f^4 , which, by engagement with the 45 inner face of the curved or C-shaped spring G serves to limit the opening movement of the lid and to prevent its being forcibly wrenching from the journal box by prying 50 on the hinged lid as a lever.

55 I claim:—
1. The combination with a journal box

having an open inner end for the axle journal to project through and provided at its outer end with an integral hinge member at the upper edge of its outer bottom end wall 60 and a curved spring seat socket adjacent thereto, of a lid having at its lower end a hinge member and a curved spring seat socket adjacent thereto, and a C-shaped spring having curved ends fitting in said 65 spring seats and surrounding and interiorly housing the hinge members of the journal box and lid, said spring seats being formed on the interior of the box and lid respectively, substantially as specified. 70

2. The combination with a journal box having an opening at its inner end for the axle journal to project through and provided at its outer end with a hinge trunnion at the upper edge of its outer bottom end 75 wall, of a lid having at its lower end a hinge socket fitting said trunnion, said lid and journal box having spring seats to receive the ends of a spring, and a curved spring having its ends fitting in said spring 80 seat sockets and operating to clamp the lid firmly and securely against the journal box at both the upper and lower ends of the lid, said spring being of a width substantially equal to the length of the hinge connection 85 and surrounding and interiorly housing the hinge members of the journal box and lid, substantially as specified.

3. The combination with a journal box having an opening at its inner end for the 90 axle journal to project through and provided at its outer end at the upper edge of its inclined bottom end wall with a hinge trunnion, of a lid having at its lower end a hinge socket fitting said trunnion, said lid 95 and journal box having spring seats to receive the ends of a spring, and a curved spring having its ends fitting in said spring seats of the journal box and lid and surrounding and interiorly housing the hinge 100 members of the box and lid, and means for limiting the opening movement of the lid to prevent the line joining said spring seats from passing the center of the trunnion, said spring serving to automatically close the lid 105 against its own gravity when the car is in motion, substantially as specified.

JOHN F. O'CONNOR.
